UNITED STATES PATENT OFFICE

JOHN J. KRATZ, OF WILKES-BARRE, PENNSYLVANIA

SHAKER APPARATUS

Application filed October 14, 1931. Serial No. 563,816.

This invention relates to improvements in shaker apparatus for use in connection with coal breakers.

The primary object of the invention resides in a means for suspending the shaker members of a shaker apparatus to enable the reciprocation thereof in the usual manner but which avoids the objection present in the type of construction now employed wherein frequent breakage is experienced in the spring suspension arms and the connection between the arms and the shaker members when in operation.

Another object of the invention is to provide a coal shaker construction wherein the shaker suspending arms are of a springy nature to facilitate longitudinal reciprocation and wherein the connection between the arms and the shaker members permits of an angular adjustment of the arms to produce a free back and forth working movement of the said shaker members.

With these and other objects in view, the invention resides in the certain novel construction, combination and arrangement of parts, the essential features of which are hereinafter fully described, are particularly pointed out in the appended claims, and are illustrated in the accompanying drawing in which:

Figure 1 is an end elevational view of a series of shaker members mounted in accordance with my invention and showing a portion of the supporting structure in cross section;

Figure 2 is a fragmentary side elevational view of the same;

Figure 3 is a fragmentary front elevational view of the lower end of one of the spring suspension arms with parts shown in section;

Figure 4 is a vertical transverse sectional view on the line 4-4 of Figure 3;

Figure 5 is a horizontal sectional view on the line 5-5 of Figure 3.

Referring to the drawing by reference characters, the numeral 10 designates a pair of spaced vertical posts which form part of a supporting structure and which posts support horizontally disposed girders or beams

11; the numeral 12 designates a coal shaker member and in Figures 1 and 2, a series of these members have been shown, the same being disposed one over the other in spaced relation and being of increasing width from the uppermost shaker member to the lowermost shaker member. These shaker members are of the conventional construction in that they are provided with a perforated body in the form of a plate 13 while angle irons 14 extend lengthwise of the body for the full length thereof to confine the coal to the shaker. It will of course be understood that the perforations in the various shaker members vary in size, that is, the uppermost shaker member is provided with larger perforations than those beneath the same. The shaker members may be of the desired length and extending transversely of the same at spaced distances are cross bars or rods 15 secured to the underside of the perforated body 13 while the ends of the rods 15 are rounded and extend outwardly beyond the opposite sides of the shaker members as at 16.

The shaker members are extended from the supporting structure by flat spring members, or arms 16, each of which is bolted or otherwise fixedly connected to cross bars 17 which bridge the spaced girders 11. A group of these arms 16 are bolted to a plurality of the cross bars 17 as illustrated in Figure 2 for the purpose of suspending the several shaker members 15 at a point adjacent each other. Connecting the lower ends of the spring arms 16 with the shaker members are universal connections, each of which comprises a plate 18, the upper end of which is formed with side flanges 19 adapted to embrace opposite sides of a spring arm 16 while passing through the plate 18 and to the lower ends of the arms 16 are securing elements in the form of bolts 20 the lower end of each plate 18 extends beyond the arm 16 to which it is connected and is rounded. Associated with the plate 18 is a bearing member which comprises a flat rounded head or gear 21 which flatly engages the plate 18 and is pivoted thereto as at 22. A bearing member is formed with a boss 23 having a bore 24 therein, the axis of which extends at right angles

to the axis of the pivot 22 and which bore receives a rounded end 16' of a rod 15. The rounded end or pintle 16' of each rod 15 extends through the bore and receives a collar 25 which prevents the sliding of the bearing member from the rod.

The head 21 is provided with opposed arcuate shaped slots 26 through which pins 27 carried by the plate 18 extend. This pin and slot connection permits of the lateral adjustment of the arm 16 to various angular positions and when adjusted, the same is secured by nuts 28 which are threaded to the outer ends of the pins 27.

With reference to Figure 1 of the drawing, it will be seen that the arms 16 are arranged in pairs for suspending opposite sides of the shaker members and which members are permitted of a free back and forth movement by reason of the pivotal connection afforded between the bearing members and the rounded ends of the cross bars 15. Due to the fact that the width of the shaker members gradually increases from the uppermost shaker member to the lowermost, the arms will be disposed at different angular positions which is permitted by the pin and slot connection between the plate 18 and the bearing member 21. Although no means has been shown to impart a back and forth or reciprocating motion to the respective shaker members, it will be understood that any means may be provided therefor as applicant's invention resides primarily in the means of supporting the shaker members in a position to be reciprocated. It is believed that the structure herein shown and described will overcome the objection in previous constructions wherein difficulty has been experienced in providing a strong connection between the spring arms and the shaker members and one which will permit of the angular adjustment of the arms relative to the said shaker members.

While I have shown and described what I deem to be the most desirable embodiment of my invention, I wish it to be understood that various changes as come within the scope of the appended claims may be resorted to if desired.

Having thus described the invention, what is claimed as new and what it is desired to secure by Letters-Patent of the United States, is;

1. A suspension device for coal shakers comprising a flat springy member, a plate fixed to one end of said member and extending therebeyond, and a bearing member pivoted to said plate and having a bore extending at right angles to the axis of the pivot, and adjustable means for preventing pivotal movement of said bearing member with respect to said plate.

2. A suspension device for coal shakers comprising a flat springy member, a plate

fixed to one end of said member and extending therebeyond, and a bearing member pivoted to said plate and having a bore extending at right angles to the axis of the pivot, and means for preventing pivotal movement of said bearing member with respect to said plate, said means including arcuate shaped slots provided in said bearing member, and threaded studs carried by said plate and extending through the respective arcuate shaped slots, and nuts threadedly connected to the free ends of said threaded studs.

In testimony whereof I affix my signature.
JOHN J. KRATZ.
